UNITED STATES PATENT OFFICE

157,749

COMBINED TOOTHBRUSH, TOOTH PASTE,
AND DRINKING GLASS SUPPORT, OR SIMILAR ARTICLE

Jules S. Garcia, New York, N. Y.

Application February 5, 1949, Serial No. 696

Term of patent 14 years

(Cl. D4—3)

To all whom it may concern:

Be it known that I, Jules S. Garcia, a citizen of the United States, and a resident of the Borough and county of Bronx, city and State of New York, have invented a new, original, and ornamental Design for a Combined Tooth Brush, Tooth Paste, and Drinking Glass Support, or Similar Article, of which the following is a specification, reference being had to the accompanying drawing, forming a part thereof, in which

Figure 1 is a side elevational view of a combined tooth brush, tooth paste, and drinking glass support, or similar article, showing my new design.

I claim:

The ornamental design for a combined tooth-brush, tooth paste, and drinking glass support, or similar article, as shown.

JULES S. GARCIA.
